UNITED STATES PATENT OFFICE.

WILLIAM I. ZIDELL, OF LOS ANGELES, CALIFORNIA.

DESIGN FOR A CHILD'S ROMPER.

54,809.

Specification for Design.

Patented Mar. 23, 1920.

Application filed July 14, 1919. Serial No. 310,867. Term of patent 14 years.

To all whom it may concern:

Be it known that I, WILLIAM I. ZIDELL, a citizen of the United States, residing at Los Angeles, in the county of Los Angeles and State of California, have invented a new, original, and ornamental Design for Children's Rompers, of which the following is a specification, reference being had to the accompanying drawing, forming part thereof.

Fig. 2 is a rear view thereof.

I claim:

The ornamental design for a child's romper, substantially as shown.

Signed at Los Angeles, California, this 8th day of July, 1919.

WILLIAM I. ZIDELL.
